Primary Examiner — Deanna L Pratt*Assistant Examiner* — Katie Mroczka(74) Attorney, Agent, or Firm — Ward & Zinna, LLC(57) CLAIM

The ornamental design for a confection, as shown and described.

DESCRIPTION

FIG. 1 is a perspective view of a confection showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in FIGS. 1 and 6 illustrate a portion of the confection which forms no part of the claimed design.

1 Claim, 7 Drawing Sheets(56)
